Application October 6, 1939, Serial No. 298,210

8 Claims. (Cl. 123—176)

This invention relates to internal combustion engines and more particularly to a means for supplying lubricating oil onto the underside of the engine pistons for cooling same and for lubricating in part the engine cylinder walls.

It is well known that lubricating oil, when sprayed into the piston results in beneficial engine performance. Prior to this, it has been attempted to spray or supply the inside of the piston with lubricating oil, but heretofore the oil has not been sprayed directly onto the piston surfaces. Most generally a continuous stream of oil is sprayed onto the crankcase in the general direction of the pistons and most of this is broken up into an oil mist and does not reach piston, resulting in a heavy oil consumption and inefficient engine operation. Such a construction, which creates an objectionable oil mist does not serve a useful purpose as regards piston cooling, since it is found that piston cooling can best be obtained by spraying lubricating oil directly in the piston so that said lubricating oil is impinged against the piston walls and internal cooling fins before same is broken up into a mist.

An object of my present invention is to provide for more efficient engine performance and decrease oil consumption by providing means controlling the supplying of lubricating oil into the piston interior so that substantially all said oil thus used is directly impinged against the walls of the piston interior.

A further object of my present invention is to facilitate the operation of a device of the character described, by constructing and arranging same for operation in timed relation with the engine crankshaft and piston so that when the engine is operating the lubricating oil is sprayed or discharged into the piston interior from a point relatively closely adjacent to the cylinder inner end, my construction providing a lubricating oil supply which is sprayed or discharged directly into the piston interior from a discharge opening carried by a connecting rod hub while said hub is traveling relatively close to the cylinder inner end.

For a more detailed understanding of my invention, reference may be had to the accompanying drawing illustrating a preferred embodiment of my invention in which like characters referred to like parts throughout the several figures of the drawing, and in which;

Fig. 1 is a plan view of an internal combustion engine.

Fig. 2 is a fragmentary plan sectional view through the aforesaid engine taken substantially

in the plane of the crankshaft, showing the relationship of the crankshaft and pistons and illustrating my improved means for supplying the piston interior with a lubricating oil.

Fig. 3 is a detailed sectional view taken on the line 3—3 Fig. 2, and

Fig. 4 is a detailed sectional view taken on the line 4—4 Fig. 3 with the crankshaft crank portion removed in order to illustrate the lubricating oil discharge opening carried in the connecting rod hub.

The present invention is shown for purpose of illustration in connection with an air-craft engine, though it is obvious that the principles of my invention may be incorporated in various types of engines and therefore is not specifically limited to an engine structure as herein illustrated. The engine A is of substantially standard construction and comprises in general, a crankcase structure 10 to which are secured a plurality of engine cylinders 11, 12, 13, and 14. The crankcase 10 carries suitable main bearings 16 which support the crankshaft 15. The cylinders each preferably include conventional cylinder liners 17, and pistons 8 are operable within each of the engine cylinders and are preferably connected with the engine crankshaft 15 by means of connecting rods 18.

It will be noted that the engine cylinders in the present embodiment are arranged in an opposed and staggered relation, and that the crankshaft is a 4-throw crankshaft of substantially standard construction. The crankshaft is provided with crank portions 15a, 15b, 15c, and 15d, the connecting rods 18 being pivotally connected to these aforesaid crank portions as clearly illustrated in Fig. 2. It will be noted that Fig. 2 is somewhat diagrammatic in that some of the structural details are omitted in order to more clearly illustrate the invention. Those portions of the connecting rods, which are pivotally connected with the said crank portions may be designated as a connecting rod hub portion and identified by the reference character 19.

Lubricating oil is fed under pressure to the main bearings 16 from any suitable source of oil supply, and I have illustrated in the accompanying drawing the main bearings 16 as being each provided with a circumferential oil groove 20, 50 that are connected with the source of oil supply in the usual way and arranged to communicate with the internal oil passages 21 in the crankshaft. It will be noted that these oil passages 21 extend through the crankshaft and con-

45

35

50

55

nect with the oil supply and terminate at the extreme outer surface of the crankshaft crank portions. It will be noted that the inertia forces aid in maintaining oil pressures at the discharge end of these passages 21.

Each of the connecting rod hubs structures 19 are provided with a passage 22 opening through the extreme outer end of the hub and thus form a jet opening or orifice 23. It will be observed 10 that the connecting rod hub structure is lined with an anti-friction bearing 24, and that this bearing 24 is provided with an elongated port 25 which communicates with the passage 22, and in the operation of the engine, it will be noted 15 that as the crank turns or rotates within the connecting rod hub that the discharge opening of passage 21 is periodically moved into communication with the elongated port 25. The length of this elongated port 25 may be varied 20 as desired and preferably it is designed to have a length which will place the passage 22 in communication with passage 21 for a period of time, and that oil is discharged from the orifice 23 while the connecting rod hub is traveling sub- 25 stantially across the inner end of one of the engine cylinders. In Fig. 3 I have shown for purposes of illustration points A and B which diagrammatically illustrate the travel of the connecting rod while said passages 21 and 22 are in 30 communication with each other. It will be seen that the length of said elongated port 25 determines how long these passages 21 and 22 are open to the pressure oil supply.

It will be noted that the connecting rod 18 associated with piston 8 in cylinder 11 has a lubricating oil jet 23 directing the oil directly into the interior of the piston associated with engine cylinder 12, while the connecting rod associated with the piston in the cylinder 12 carries an oil jet directing oil into the piston associated with cylinder 11. Likewise the pistons associated with cylinders 13 and 14 are respectively supplied with lubricating oil from oil jet openings carried by the connecting rods associated with cylinder 14 and 13.

It will be seen that the cylinders are arranged so that the connecting rod hubs travel closely adjacent to the inner end of an adjacent cylinder. The oil passages are so constructed and arranged and the crankshaft and pistons are so operatively timed as to preferably only supply lubricating oil directly into the piston interior, while the piston is at the bottom of its stroke, and the connecting rod hub from which the oil is discharged is traveling closely adjacent to the cylinders inner end and underside of the piston.

In the cylinder arrangement as herein illustrated, it will be obviously seen that the construction and arrangement is very readily timed in operation to obtain the desired results. Other cylinder arrangements may be as readily timed and constructed to accomplish the same purpose. In the present type of engine the engine performance has been materially improved by reason of this auxiliary supply of lubricating oil directly into the piston interior. It will be observed that the lubricating oil has only a short distance to travel before it impinges on the interior piston walls, and thus the tendency of this lubricating oil to break up into a mist prior to being impinged on the piston is practically eliminated. I thus obtain efficient cooling of the system with a minimum of oil consumption, since substantially all of the oil is directly discharged onto the

piston surfaces as desired and only a negligible amount of oil reached the cylinder wall from whence it will eventually reach the combustion chamber. Thus the necessity of supplying additional oil draining rings is eliminated. Some of the oil reaches the cylinder walls and thus helps in lubricating same.

Although I have illustrated my invention in connection with a preferred embodiment it will be apparent that various changes and modifications may be made therein without departing from the spirit of my invention or from the scope of the appended claims.

I claim:

1. In an internal combustion engine, the combination of a plurality of cylinders, a crankshaft having a radially offset portion, a piston operable in each of said cylinders and connected with said crankshaft, said crankshaft having lubricant conducting means in said offset portion, and means operable in timed relation with said crankshaft and piston for discharging lubricant from said conducting means to the underside of said piston when said piston is adjacent the bottom of its stroke and relatively closely adjacent to said offset portion.

2. In an internal combustion engine having a plurality of cylinders, a multithrow crankshaft, pistons operable in said cylinders and each connected with a throw of the crankshaft, means conducting lubricant under pressure through said crankshaft and including a discharge opening located substantially at the extreme outer portion of each crankshaft throw, and means controlling the ejection of lubricant from the discharge opening and operable in timed relation with said crankshaft during engine operation to discharge the lubricant outwardly of the crankshaft throw, and impinge same against the underside of said pistons when said pistons are substantially adjacent the bottom of its stroke and adjacent to one of said discharge openings.

3. In an internal combustion engine having a plurality of cylinders, a crankshaft having a plurality of crank portions, pistons operable in said cylinders, connecting rods operatively connecting each of said pistons with one of said crankshaft portions, said crankshaft having a lubricant passage for conducting lubricant under pressure and including a discharge orifice located substantially at the extreme outer portion of each crank portion, each of said connecting rods having a hub pivotally connected with the crankshaft crank portion, said connecting rod hub having a discharge opening constructed and arranged to sweep over the crankshaft lubricant discharge orifice and arranged for operation in timed relation with said crankshaft and pistons, to discharge the lubricant and impinge same against the underside of the piston in the adjacent cylinder when said piston is substantially travelling adjacent the cylinder inner end substantially closely adjacent to said discharge opening aforesaid.

4. In an internal combustion engine having a plurality of cylinders, a crankshaft having a plurality of crank portions, pistons operable in said cylinders, connecting rods operatively connecting each of said pistons with one of said crankshaft portions, said crankshaft having a lubricant passage for conducting lubricant under pressure and including a discharge orifice located substantially at the extreme outer portion of each crank portion, each of said connecting rods having a hub pivotally connected with the crankshaft crank

portion, each of said connecting rod hubs having a discharge opening constructed and arranged for periodical communication with the crankshaft lubricant discharge orifice and arranged for operation in timed relation with said crankshaft and pistons, to spray the lubricant against the underside of the piston in an adjacent cylinder when said connecting rod hubs are travelling in close proximity to the cylinder inner end, and when the 10 pistons are near the bottom of their stroke.

5. In an internal combustion engine having a plurality of cylinders, a crankshaft having a plurality of crank portions, pistons operable in said cylinders, connecting rods operatively connecting 15 each of said pistons with one of said crankshaft portions, said crankshaft having a lubricant passage for conducting lubricant under pressure and including a discharge orifice located substantially at the extreme outer portion of each crank portion, each of said connecting rods having a hub pivotally connected with the crankshaft crank portion, each of said connecting rod hubs having a elongated discharge opening constructed and arranged for periodical communication with the 20 crankshaft lubricant discharge orifice and arranged for operation in timed relation with said crankshaft and pistons, to spray the lubricant against the underside of a piston in an adjacent cylinder when said connecting rod hubs are travelling in close proximity to the cylinder inner end, and when the pistons are near the bottom of their stroke.

6. In an internal combustion engine including 25 a pair of engine cylinders axially offset, a crankshaft having crank portions substantially aligned with the cylinders, pistons operating in said cylinders, connecting rods connecting the pistons with the crank portions of said crankshaft, said pistons and crankshaft operatively timed in operation to place the piston in one cylinder at the 30 bottom of its stroke and closely adjacent the cylinder inner end when the crank portion aligned with said other cylinder is travelling substantially closely adjacent the first mentioned cylinder, means conducting lubricating oil under pressure to the surface of the crank portion adjacent the piston, and means timed in operation with the crankshaft to control the discharge of the 35 lubricating oil, whereby to spray the oil directly into the piston while same is substantially at the bottom of its stroke.

into the piston while same is substantially at the bottom of its stroke.

7. In an internal combustion engine including a pair of opposed engine cylinders axially offset, a crankshaft having crank portions substantially aligned with the cylinders, and offset 180 degrees from each other, pistons operating in said cylinders, connecting rods connecting the pistons with the crank portions of said crankshaft, said pistons and crankshaft operatively timed in operation to place the piston in one cylinder at the bottom of its stroke and closely adjacent the cylinder inner end when the crank portion aligned with said other cylinder is travelling substantially closely adjacent the first mentioned cylinder, means conducting lubricating oil under pressure to the surface of the crank portion adjacent the piston, and means timed in operation with the crankshaft to control the discharge of the lubricating oil, whereby to spray the oil directly 20 into the piston while same is substantially at the bottom of its stroke.

8. In an internal combustion engine including a pair of engine cylinders axially offset, a crankshaft having crank portions substantially aligned 25 with the cylinders, pistons operating in said cylinders, connecting rods connecting the pistons with the crank portions of said crankshaft, said pistons and crankshaft operatively timed in operation to place the piston in one cylinder at the 30 bottom of its stroke and closely adjacent the cylinder inner end when the crank portion aligned with said other cylinder is travelling substantially closely adjacent the first mentioned cylinder, means conducting lubricating oil under pressure to the surface of the crank portion adjacent the piston, and means timed in operation with the crankshaft to control the discharge of the lubricating oil, whereby to spray the oil directly 35 into the piston while same is substantially at the bottom of its stroke, said lubricating oil conducting means comprising oil conducting passages connecting the source of lubricating oil under pressure with the outer surface portion of the crankshaft crank portion, said oil discharge control 40 means comprising a passage in said connecting rod portion arranged for periodic alignment with the passage in said crankshaft during engine operation.
